UNITED STATES PATENT OFFICE

154,018

DESIGN FOR A FINGER RING OR THE LIKE

Nicholas Barbieri, Providence, R. I., assignor to
 Uncas Manufacturing Company, a corporation
 of Rhode Island

Application September 29, 1947, Serial No. 141,633

Term of patent 14 years

(Cl. D45—10)

To all whom it may concern:

Be it known that I, Nicholas Barbieri, a citizen of the United States of America, residing at Providence, county of Providence, State of Rhode Island, have invented a new, original, and ornamental Design for a Finger Ring or the like, of which the following is a specification, reference being had to the accompanying drawing, forming a part thereof.

Fig. 1 is a perspective view showing my new design for a finger ring or the like; and

Fig. 2 is an edge elevation thereof.

I claim:

The ornamental design for a finger ring or the like, substantially as shown.

NICHOLAS BARBIERI.
